US00D378218S

United States Patent

[19]

Hong et al.

[11] Patent Number: Des. 378,218

[45] Date of Patent: **Feb. 25, 1997

[54] COLOR PRINTER

[75] Inventors: **Yun K. Hong, Suwon; Byung S. Jung, Seoul, both of Rep. of Korea**[73] Assignee: **Samsung Electronics Co., Ltd., Kyunggi Do, Rep. of Korea**

[**] Term: 14 Years

[21] Appl. No.: 40,075

[22] Filed: Jun. 9, 1995

[30] Foreign Application Priority Data

Dec. 10, 1994 [KR] Rep. of Korea 26642

[52] U.S. Cl. D18/55

[58] Field of Search D18/50, 54-55; 400/613, 613.1-613.4, 690.1-690.4, 691-694
